Attest:

UNITED STATES PATENT OFFICE

92,867

DESIGN FOR A CASKET

Harry S. Scholl and Richard J. Donnelly, Chicago,
Ill., assignors to F. H. Hill Company, Inc., Cleve-
land, Ohio, a corporation of Ohio

Application June 7, 1934, Serial No. 52,105

Term of patent 7 years

To all whom it may concern:

Be it known that we, HARRY S. SCHOLL and RICHARD J. DONNELLY, citizens of the United States, residing at Chicago, in the county of Cook, State of Illinois, have invented a new, original, and ornamental Design for Caskets, of which the following is a specification, reference being had to the accompanying drawing, forming a part thereof,

Fig. 1 is a perspective view of a casket showing our new design; and

Fig. 2 is an end view of the casket shown in Fig. 1.

We claim:

The ornamental design for a casket as shown.

HARRY S. SCHOLL.
RICHARD J. DONNELLY.
